M. B. LLOYD

METHOD OF PRODUCING REED ARTICLES

Filed Aug. 20, 1920

Marshall B. LLOYD INVENTOR.
BY *Arthur W. Nelson*
ATTORNEYS.

UNITED STATES PATENT OFFICE.

MARSHALL B. LLOYD, OF MENOMINEE, MICHIGAN, ASSIGNOR, BY MESNE ASSIGNMENTS, TO LEVI H. GREENWOOD AND GEORGE A. KEYWORTH, BOTH OF GARDNER, MASSACHUSETTS, AND WILLIAM E. HOLMAN, OF LEOMINSTER, MASSACHUSETTS, TRUSTEES.

METHOD OF PRODUCING REED ARTICLES.

Application filed August 20, 1920. Serial No. 404,795.

To all whom it may concern:

Be it known that I, MARSHALL B. LLOYD, a citizen of the United States, and a resident of Menominee, county of Menominee, 5 and State of Michigan, have invented certain new and useful Improvements in Methods of Producing Reed Articles, of which the following is a specification.

My invention relates generally to the production of reed articles that are composed 10 of a frame and an independently woven reed fabric. This type of article, and the general methods for the production thereof, is disclosed in Patents Nos. 1,243,079, 1,243,080, 15 1,243,081 and 1,243,082, granted to me October 16, 1917.

My inventions, of which the above mentioned patents are illustrations established 20 the practice of producing reed articles by making the reed fabric independent of the frame, in a manner convenient for the weaving operation, and thereafter placing the fabric upon and securing it to the frame. It is desirable that the fabric applied to 25 the article frame shall have the appearance of being woven into the frame as is characteristic of those articles which are produced under former methods wherein the stakes are secured in the frame and the fabric woven thereon.

The general object of my invention is to provide a method whereby reed articles having a frame can be produced by making the fabric independently of the frame and 35 thereafter applying it to the frame in such manner that the resulting articles shall in appearance be similar to that of articles wherein the fabric is woven as a part of the frame.

It is also an object of my invention to provide a method of producing reed articles having a frame and an independently woven reed fabric whereby the fabric can very easily be secured to the frame with such a degree of permanence as in effect to constitute 45 a part thereof.

It is also an object of my invention to provide a reed article having an independently woven reed fabric that shall be of durable character, of pleasing appearance, and which shall be of such construction as to lend itself to quantity production by unskilled workers.

My invention consists generally in an

article of manufacture, and in the steps, acts 55 and stated sequence thereof for producing such an article, whereby the above named objects, together with others that will appear hereinafter, are attainable; and my invention will be more readily understood by 60 reference to the accompanying drawings which illustrate what I consider at the present time to be the preferred embodiment thereof.

In said drawings:

Fig. 1, is a plan view of a piece of fabric prepared for application to the back of a chair.

Fig. 2 is a perspective view of the frame of a chair for the back of which the fabric 70 shown in Fig. 1 is designed.

Fig. 3 is a perspective view of the chair in its completed form.

Fig. 4 is a sectional view substantially on the line 4—4 of Fig. 3.

Fig. 5 is a perspective view of an endless or tubular reed fabric designed for application to the back of a chair.

Fig. 6 is a perspective view of a chair to the back of which the fabric of Fig. 5 is 80 applied.

Fig. 7 is a sectional view substantially on the line 7—7 of Fig. 6.

Fig. 8 is a perspective view of a tubular reed fabric designed for the bottom part of 85 the chair.

Fig. 9 is a perspective view of a chair to which a fabric of the character shown in Fig. 8 is applied.

Fig. 10 is a sectional view substantially on 90 the line 10—10 of Fig. 9; and

Fig. 11 is a perspective view of another form of reed article manufactured in accordance with my invention.

Only a few types of reed articles are 95 shown in the drawings but these, it should be understood, are by way of illustration only and not by way of limitation.

Referring now particularly to Figs. 1 to 4 of the drawings, 1, represents the frame 100 of a chair which may be of usual or desired construction. As here shown, the bottom of the chair is composed of rigidly connected board members 2 arranged in rectangular form. Downwardly therefrom depend the 105 legs 5 and upwardly at the rear will be found the side vertical members 4 which are cross connected as by means of the mem-

bers 6 and 7. The rear legs are also cross connected as by member 3. The members 4, 6 and 7 constitute the back of the chair frame and as here shown they are circular in cross section, i. e. of the dowel like form extensively used in the production of reed articles.

With respect to Figs. 1 to 4 inclusive I shall describe only the construction of the 10 back and in Fig. 3 the bottom of the chair is shown with fabric applied thereto simply to illustrate how the completed article will appear.

As before intimated the fabric which is to 15 cover the back is woven independently of the frame and a piece of suitable size is shown in Fig. 1. The reed fabric is composed of a plurality of spaced stake members 8 around which filler strands 9 are intertwined. The stake members 8 are ordinarily 20 relatively stiff and rigid and resist to a considerable degree any tendency to bend or kink them whereas the filler strands 9 are of a more pliable character and are readily 25 intertwined around the stakes. Because of the relative rigidity of the stake members and their somewhat large size they do not lend themselves readily to shaping around the dowel members of the frame and in any 30 event they are so pronounced as to accentuate the fact that the fabric is applied to and not woven on the frame. This is one of the features which it is the object of my invention to overcome. I might here state 35 that where reed articles are manufactured by the usual hand method of securing the stakes in the article frame and weaving the filler strand over and under the stakes it is the customary practice to wrap the filler 40 strand around the end frame members. This serves as a means of tying the fabric to the frame and at the same time serves to provide a very pleasing fibre finish to the frame members.

45 I have devised a method of simulating this wrapped characteristic in an article in which the fabric is woven independently of the frame. To this end I provide a piece of reed fabric the body of which is provided 50 with regularly spaced stake members but which along the edge portions has one or more of the stakes omitted thus providing strip portions as indicated at 10 and 11 in Fig. 1 which consist only of filler strands. I 55 prefer to bind the extreme edges of the portions 10 and 11 as by means of metallic binder strips 12 and 13 which strips may, if desired be of the form disclosed in my Patent No. 1,336,571, dated April 13, 1920.

60 I am not concerned vitally with the manner in which a fabric of this character is provided and it may be provided either by originally weaving it with portions in which the stakes are omitted or it may be regularly 65 formed fabric, i. e. a reed fabric in which

stakes are spaced throughout initially and then one or more of the stakes withdrawn to provide the desired effect.

Having provided a piece of fabric of the character shown in Fig. 1, I apply this to 70 the frame by wrapping the strip portions 10 and 11 around the dowel frame members 4, preferably securing the metallic strip portions to the rear parts of the frame members 4 as is well shown in Fig. 4. In this position the metallic binder strips are hidden from view and do not therefore detract from the appearance of the article. At the same time by wrapping the filler strand strip portions around the dowel like frame members most of the strains to which the back is subjected in use will be taken by the frame members 4. That is to say—no direct pull will be imposed upon the fastening devices 75 tending to loosen them from the frame. 80

It will be observed that the body portion of the fabric i. e. that portion containing the stakes is of sufficient width just to fill the space between the vertical frame members 4. By this construction the frame members of 85 the article present an appearance which is practically indistinguishable from the wrapped appearance heretofore characteristic of those articles in which the fabric is woven as a part of the frame. Also by the 90 construction herein shown the permanence of the fastening is practically equal to that wherein the fabric is tied to the frame in the course of weaving.

In the construction shown in Figs. 1 to 4 100 it is possible to see the fastening means if careful inspection be made of the reverse side of the back and for some of the more expensive articles this may not be desirable.

In Figs. 5, 6 and 7 I have illustrated an 105 article and a method of producing the same in which this feature is obviated. The chair shown in Fig. 6 may have a frame substantially like that shown in Fig. 2, and while the lower part of the chair is shown with 110 fabric thereon only the upper or back of the chair will be described, inasmuch as that is the particular feature of interest.

For the manufacture of the chair back shown in Fig. 6 I first produce a tubular fabric (see Fig. 5) which is composed of a plurality of stake members 14 around which filler strands 15 are intertwined. At diametrically opposite zones I provide the strip portions 16 which are composed only of filler 115 strands. As in the case of fabric shown in the Fig. 1 it may be provided in any desirable manner as by producing a fabric of the usual form and thereafter removing the desired number of stakes or by initially producing a fabric from which stakes have been omitted along those zones or portions. The tubular fabric shown in Fig. 5 is of a size such as snugly to encompass the end members 4 of the frame, best shown in Fig. 7, 120 125 130

and the strip portions 16 are positioned to embrace or form themselves around the outer parts of the frame members 4. By this arrangement the same wrapped appearance 5 characteristic of the article described with reference to Figs. 1 to 4 is produced and at the same time no fastening device of any nature is discernable no matter from what angle the article may be viewed. Because 10 of the encompassing relation of the tubular fabric to the spaced frame members there is a natural tendency for the fabric to adhere to the frame, and hence but little additional fastening means is required.

15 The same general method of construction is suitable for providing the bottom of a chair and such a construction is illustrated in Figs. 8, 9 and 10. Inasmuch as there are four legs over which the fabric is to pass, 20 I provide four strip portions 17 (see Fig. 8) from which the stakes have been omitted. This fabric is placed over the frame and the portions 17 are partly wrapped around the leg portions as is well shown in Figs. 9 and 25 10, thereby presenting the desired characteristics heretofore enumerated.

Fig. 11 illustrates another form of article having four legs or standards 18 around which tubular fabric similar to that shown 30 in Fig. 8 may be wrapped thus presenting, as at 19, the desired characteristic indicative of the intimate union between the frame and the fabric.

Reed articles are much used where appearance 35 is quite as important as utility and the method herein shown and described and the article produced thereby result in greatly enhancing the appearance of the article as well as reducing its cost and increasing its durability.

In qualifying the fabric or its elements as "reed" in the specification or claims, I mean to limit my invention to fabric, the elements 45 of which co-operate in the manner above described as characteristic of the stake and strand fabric made of reed, but to embrace such materials whether they be the natural reed, paper reed, or other materials having the general characteristics of reed.

50 The many advantages of the article and

the method for producing the same will be understood by those skilled in this art without further comment.

I claim:

1. The method of producing reed articles 55 that consists in providing a frame, in providing an independently woven piece of reed fabric having along one side thereof a portion that is composed only of filler strands and the ends of which are secured by a binder strip, and in securing the fabric to the frame so that the filler strand portion is positioned over the frame member with the binder strip upon the rear side of said frame member. 60

2. The method of producing reed articles 65 that consists in providing a frame, in providing an independently woven piece of reed fabric having along one side thereof a portion from which at least one stake has been omitted and the edge portion of which is embraced by a binder strip, and in securing the fabric to the frame so that the filler strand portion is positioned over the frame member with the binder strip upon the rear side of said frame member. 70

3. The method of producing reed articles 75 that consists in providing a frame, in providing an independently woven piece of reed fabric having along opposite sides thereof 80 portions that are composed only of filler strands and the ends of which are secured in binder strips, and in securing the fabric to the frame by wrapping the filler strand portion around the frame member and securing the binder strips to the frame member. 85

4. The method of producing reed articles 90 that consists in providing a frame, in providing an independently woven piece of reed fabric having along opposite sides thereof 95 portions from which at least one stake has been omitted, and the edges of which are secured in binder strips, and in securing the fabric to the frame by wrapping the filler strand portion around the frame member and securing the binder strips to the frame member.

In testimony whereof, I have hereunto set my hand, this 26th day of July, 1920.

MARSHALL B. LLOYD.
